UNITED STATES PATENT OFFICE.

CHARLES EDMUND KELLS, OF NEW ORLEANS, LOUISIANA.

METHOD FOR SURGICALLY CLEANSING WOUNDS AND OTHER SURFACES.

1,114,268.

Specification of Letters Patent.

Patented Oct. 20, 1914.

Application filed October 14, 1913. Serial No. 795,059.

To all whom it may concern:

Be it known that I, CHARLES EDMUND KELLS, a citizen of the United States, residing at New Orleans, in the parish of Orleans and State of Louisiana, have invented a new and useful Improvement in Methods for Surgically Cleansing Wounds and other Surfaces, of which the following is a specification.

10 My invention relates to an improved method for surgically cleansing wounds and other surfaces, its object being to provide a procedure having the benefits and advantages hereinafter appearing.

15 The method can profitably be practised in connection with devices of different characters, two of such devices being shown in the accompanying drawings, in which:—

Figure 1 is a perspective view of one device for the practice of this invention; Fig. 2 is a longitudinal section through the device of Fig. 1; Fig. 3 is a longitudinal section through another form of the apparatus, and Fig. 4 is a section on the line 4 of Fig. 3.

25 In the use of the device of Figs. 1 and 2, for the practice of my method, the cleansing fluid, usually an antiseptic solution, enters through a tube 5, the tip of which is turned in at 6 and enters a tube 7, the rear end of 30 the tube 7 being connected by a rubber tube to a suction apparatus. The tube 7 is closed at its operative end by means of a gauze 8. The fluid issuing from the tip 6 of the tube 5 flows out upon the surface to be operated 35 upon and does its work over a confined area, and is immediately sucked back into the tube 7 and carried away. The flow of the fluid can be readily controlled by pressure of the hand on the rubber tube shown, al- 40 though, of course, other forms of regulating appliances can be adopted.

In the device shown in Figs. 3 and 4, the tube 5 with its tip 6 is substantially of the same form. The suction tube 7, however, 45 terminates in an enlarged chamber 9, in which is mounted a swab 10. As the fluid flows down it wets this swab, which can be used in mopping the surface to be 50 cleansed, and the fluid is constantly drawn up through the swab, so that none flows away.

The method can be practised with many other forms of apparatus, these two being selected, as samples, to illustrate the principle.

It will be noticed that in their operation

the cleansing fluid is applied to a very small and restricted area and that although there is ample quantity of the fluid to do the cleansing work, it is immediately picked up by suction and drawn away. Thus, while the surface is thoroughly cleansed at the spot to which the device is applied, the cleansing fluid has no opportunity to flow from the spot under the immediate treatment to some other part of the surface or wound, thereby physically carrying with it dirt and so possibly spreading infection. This method of operation is peculiarly advantageous as compared with prior methods because it renders it possible to use ample quantity of fluid for the most thorough cleansing without any possibility of spreading infection by the flow of the fluid from one part of the wound, or surface, to another. Heretofore, surgical cleansing has either been performed by swabs, sponges, or the like, in which case, the fluid was necessarily of but limited quantity, or else if the cleansing was done with fluid in a stream, or in such a copious amount as to keep a swab or sponge dripping wet, it ran from place to place, carrying with it bodily the dislodged dirt from one place to another with the greatest danger of spreading infection. With the present method, on the contrary, the wound, or surface, is washed part by part, each part thoroughly, and with ample fluid, but the fluid is completely confined to the spot under operation and cannot flow away.

As hereinbefore stated, the method is entirely independent of any particular apparatus employed, and the particular manner in which it is carried out, and I, therefore, do not intend to limit myself to the particular procedure set forth, except as pointed out in the following claim, in which it is my intention to claim all the novelty inherent in the process as broadly as is permitted by the state of the art.

I claim as new and desire to secure by Letters Patent:—

The herein described improvement in the art of surgically washing wounds, which 105 consists in discharging a cleansing fluid in limited volume and in close proximity to the wound to be cleansed to cause such cleansing fluid to flow in a thin film over relatively larger areas of such wound, and immediately withdrawing said cleansing fluid with the suspended matter carried thereby by suc-

tion exerted adjacent its point of application, whereby the cleansing fluid covers successive areas of the wound, and the spread of dislodged matter from each area beyond the boundaries thereof as the same is washed is prevented.

In testimony whereof I have hereunto set my hand this 29 day of September, 1913.

CHARLES EDMUND KELLS.
